(57) **CLAIM**

The ornamental design for a grooming hair accumulator for animal, as shown and described.

DESCRIPTION

FIG. 1 is a top perspective view of a grooming hair accumulator for animal, showing our new design.

FIG. 2 is a bottom perspective view thereof;

FIG. 3 is a top plan view thereof;

FIG. 4 is a bottom plan view thereof;

FIG. 5 is a right side view, the left side view being a mirror image thereof;

FIG. 6 is another perspective view, but shown with the handle and head separated for completeness of illustration.

FIG. 7 is another perspective view, but shown with the handle removed for completeness of illustration.

FIG. 8 is another perspective view thereof; and,

FIG. 9 is another perspective view thereof.

The broken lines illustrate portions of the grooming hair accumulator for animal that forms no part of the claimed design.
